UNITED STATES PATENT OFFICE.

ALBERT A. GRANOVSKY, OF NEW YORK, N. Y.

VERMINPROOF MATTRESS.

Application filed October 7, 1924. Serial No. 742,209.

To all whom it may concern:

Be it known that I, ALBERT A. GRANOVSKY, a citizen of the United States, and a resident of the borough and county of Bronx, city and State of New York, have invented certain new and useful Improvements in Verminproof Mattresses, set forth in the following specification.

This invention relates to box bed spring construction. The object of the invention is both to simplify the construction of such a structure and to produce one which is absolutely vermin proof and which stays vermin proof in use. To these ends, a minimum of wood framing is contemplated and the coordination of a simple wooden frame with an unbroken undersurface to serve as one jaw of clamping means to seal the margins of a covering and a bottom cover of ticking 20 through the medium of a supporting strip forming the other jaw.

The above and further objects of the invention will be set forth more particularly in the claim which is directed for purposes 25 of illustration to the illustrative embodiments of the invention described in the following specification in connection with the accompanying drawings which form part hereof. The disclosure of the illustrative 30 embodiments herein is merely for purposes of illustration and not limitation.

In the drawings, Fig. 1 is an end view, with parts broken away, of the finished construction;

Fig. 2 is a bottom view parts being shown in dotted lines;

Fig. 3 is a cross-section through the bottom frame showing a perfect form at this locality;

Fig. 4 is a similar view showing a modification;

Fig. 5 is a fractional bottom view of a corner of the structure showing one modification of the vermin seal and support;

Fig. 6 is a cross-section through the plane of line VI—VI of Fig. 5;

Fig. 7 is a view corresponding to Fig. 5, showing a modification; and

Fig. 8 is a similar view showing another modification.

A strong rectangular wooden frame A preferably having morticed corners 1, as indicated in Fig. 6, is provided and fabricated so that its bottom face 2 throughout 55 is an unbroken smooth surface, preferably flat.

Extending cross-wise of this frame A is a series of cross-slats 4 suitably secured at their ends 5 to the frame A. Mounted upon and upwardly extending from the slats 4 are rows of compression springs 6 reacting between the slats and the mattress portion 7 which may be of usual hair-stuffed construction or of any other usual make-up. A covering B of ticking, imperforate throughout and vermin tight, extends over the entire top and sides of the structure with its margin 8 underlapping and lying flat against the bottom face 2 of the frame A, to which it may be independently secured by a series of tacks 9. This is easy of accomplishment with the structure placed upside down for the fabrication and requires no expensive frame construction. The opening in the frame A is then covered by a stretched cover C of ticking with its margin 10 secured to the bottom face of the frame A in a suitable manner as by a series of tacks 11. With the covering B and the bottom cover A thus secured, the covering and cover are well held mechanically in position, but are not vermin tight. Furthermore, they are far from being protected against accidental injury at their margins to increase the size of vermin openings. To remedy this feature, it is preferred that the locality of the margins, as for example, the irregular opening 12 between the margins 8 and 10, be smeared with a sealing dope such as melted rosin, hot glue, paraffin, or the like. There is then preferably applied, so as to overlap a portion of both margins 8 and 10, a protective bridging strip. This may be a half-round wooden bead D as shown in Figure 3, suitably secured as by brads 14 so as to clamp the intermediate filling of dope 15 tightly upon both margins 8 and 10 and into the space there-between. When the bead D is employed, it should be mitered at the corners and the dope filled into the mitered joints.

Again, if desired, metal strips D' may be substituted for half-round bead D, in which case double rows of brads 16 and 17 may be employed to secure the strips. In this case, also, the dope filling is preferred and should involve the mitered joint 18.

If desired also, the side edges 21 and 22 of such a metal strip may be bent upwardly as shown in Figure 6, the better to confine the dope filling 15.

Again, if desired, a continuous metal strip D'', as shown in Figure 7, may be employed,

in which a simple fold 23 may be substituted for the mitered corners; also, as shown in Figure 8, this strip may have a double fold 24 so as to make a square corner.

In this construction, the reinforcing members D, D', etc., serve the dual function of completing the vermin seal between the covering and the cover and also serve as a mechanical resistant support for the entire construction, the sealing dope and the margins of the covering and cover being gripped between the smooth unbroken surface of the frame and this reinforcing strip. It is also contemplated that for some purposes the interposition of the dope filling may be done away with, or serve as the means for securing the strip without brads or tacks.

The inventive thought may have a variety of expressions as is contemplated by what I claim and desire to secure by United States Letters Patent as follows:

A vermin proof box bed-spring construction comprising an open rectangular bottom frame having a smooth unbroken bottom face; a series of cross-slats extending cross-wise of said frame and secured relatively

thereto leaving the bottom face of said frame as an unbroken smooth surface; a top mattress portion spaced apart from said slats; compression springs reacting between said slats and said mattress portion; a vermin tight cover of ticking covering said mattress portion, the sides of the structure and overlapping a portion of the said unbroken bottom face of said frame with its margin secured thereto; a bottom cover of ticking stretched across the opening of said frame and having its margin overlapping a portion of said bottom face of said frame and being secured thereto; a combination supporting strip and vermin seal overlapping both the margin of said cover of ticking and said bottom cover forming a vermin seal therewith and extending down to form a mechanically resistant support for the entire structure and itself located wholly inside of the outer edges of the sides of the structure.

In witness whereof, I have signed my name to this specification this 12th day of June, 1924.

ALBERT A. GRANOVSKY.
